UNITED STATES PATENT OFFICE.

GEORGE R. HOGAN AND HECTOR P. MACLAGAN, OF CHICAGO, ILLINOIS.

CABINET FOR X-RAY APPARATUS.

1,175,450.

Specification of Letters Patent. Patented Mar. 14, 1916.

Application filed April 13, 1914. Serial No. 831,371.

To all whom it may concern:

Be it known that we, GEORGE R. HOGAN and HECTOR P. MACLAGAN, citizens of the United States, residing at Chicago, in the county of Cook and State of Illinois, have invented certain new and useful Improvements in Cabinets for X-Ray Apparatus, of which the following is a full, clear, concise, and exact description, reference being had to the accompanying drawings, forming a part of this specification.

Our invention relates to an improved apparatus for controlling the operation of X-ray tubes and at the same time protecting the operator from the injurious influence of the X-rays emanating from the tubes employed.

In carrying out our invention the apparatus used for developing the high tension current required to operate the X-ray tubes is mounted in a suitable cabinet provided with a switch-board supporting desired controlling apparatus for operating the mechanism in the cabinet. The cabinet is also provided with a door for inclosing the switch-board, which door when in its open position serves as a screen for the operator to prevent stray rays passing from the tube to the operator.

30 The several drawings illustrating our invention are as follows:

Figure 1 shows in perspective, a view of the complete cabinet; Fig. 2 shows a view of the cabinet with the front side wall removed; Fig. 3 shows an end view of the cabinet with the door used to inclose the switch-board removed.

Similar numerals refer to similar parts throughout the several views.

40 As shown in the drawings, the cabinet 1 contains a rotary converter 2 and a transformer 3, these devices being separated from the compartment containing the switch-board by means of a partition 4. Upon this partition the switch-board 5 is mounted, and upon this switch-board, as seen in Fig. 3, a main switch 6 and starting rheostat 7, flashing switch 8, and controlling knob 9 for the potential rheostat, regulating switches 10 and an ammeter 11, are mounted.

45 The partition 4 is far enough from the right hand end of the cabinet so that all of the apparatus mounted upon the switch-board may be inclosed by means of a door 12, pivoted to the right hand edge of the front side of the cabinet. The cabinet may

have mounted upon its front outer wall control electrodes 13 and adjustable flexible conductors 14, if desired, for connecting the terminals of the transformer 3 to the X-ray 60 tube to be operated.

The door 12 is constructed in such a manner as to serve not only to inclose the switch-board and the apparatus mounted thereon, but also to serve as a screen or shield for the operator, who preferably stands during the operation of the mechanism in close proximity to the switch-board 5. To secure this desirable result the inner surface of the door 12 is provided with a covering 15 of sheet lead, which extends over its entire surface, assuming the door to be low enough so that the operator can look over it. To provide a screen for the head of the operator, for such a proportion of cabinet, the door 12 is 75 provided with an extension slide 16 mounted in guideways 17 on the rear surface of the door so that when the door is open the extension may be raised to the position indicated in Fig. 1, for which position the top of the extension is provided with a window 18 of lead glass, through which the operator may look, and with the exception of this window the surface of the extension 16 is 80 preferably covered with sheet lead so as to 85 make it an effective screen to prevent X-rays straying from the X-ray tube penetrating through the screen and injuring the operator. The extension 16 may be held in its upper position by means of any suitable 90 catches, not shown.

For large cabinets in which the door 12 is higher than the operator the extension 16 may be dispensed with, and for this proportion of cabinet a window 18^a is located in 95 the upper portion of the door itself, the opening being closed by a pane of lead glass, as described above for the extension 16.

We find it desirable in connection with the screen constructed as described above, to provide for certain purposes a fluorescent screen 19, which may be moved by the operator into the path of the rays coming to the window 18 or 18^a as the case may be, which fluorescent screen is preferably so mounted that it may be moved into the field or from the field while the operator is fully protected back of the door 12. A convenient means for operating the screen 19 is indicated in Figs. 1 and 2, consisting in providing supporting cords 20, which pass around rollers 21 supported by the upper edge of 105 110

the extension 16, or for large size of the cabinet by the upper edge of the door 12, the ends of the cords extending back of the door and extension within easy reach of the operator, so that he may by operating the cords move the screen 19, either into position in front of the window or remove the screen from such position, as desired.

As a result of the construction described, 10 the use of a separate screen for protecting the operator is dispensed with and the operator's protecting screen and the cabinet containing the operating apparatus are combined in compact form. The cabinet is 15 preferably provided with rear doors 22 for permitting examination of the apparatus in the cabinet.

While we have shown our invention in the particular embodiment herein described, we 20 do not wish to be understood as limiting ourselves to this particular construction, as we may employ equivalents of the devices shown, without departing from the spirit of our invention.

25 What we claim is:

1. In a device of the class described, the combination of a plurality of walls constituting a part of a cabinet for containing electrical apparatus, and a door for closing 30 the end of said cabinet, said door comprising in part a surface of material opaque to X-rays, a frame mounted upon the door and movable to a position extending above the top of the door, and a pane of glass 35 opaque to X-rays carried by said frame.

2. In a device of the class described, the combination of a plurality of walls constituting a part of a cabinet for containing electrical apparatus, and a door for closing 40 the end of said cabinet, said door comprising in part a surface of material opaque to X-rays, vertical guideways carried by the back of the door, a frame slidably mounted in said guideways so that said frame may 45 extend above the top of the door, and a pane of glass opaque to X-rays mounted in said frame.

3. In a device of the class described, the combination of a plurality of walls constituting a part of a cabinet for containing 50 electrical apparatus, and a door for closing the end of said cabinet, said door comprising in part a surface of material opaque to X-rays, and an extension screen opaque to 55 X-rays carried by said door and movable relatively thereto to project above the top of said door.

4. In a device of the class described, the combination of a plurality of walls constituting 60 a part of a cabinet for containing electrical apparatus, and a door for closing the end of said cabinet, said door comprising in part a surface of material opaque to X-rays, a frame mounted upon the door and movable to a position extending above the top 65

of the door, and a pane of glass opaque to X-rays carried by said frame, said frame comprising in part a sheet of material opaque to X-rays.

5. In a device of the class described, the combination of a plurality of walls constituting a part of a cabinet for containing electrical apparatus, and a door for closing the end of said cabinet, said door comprising in part a surface of material opaque to 75 X-rays, and a window-pane of glass opaque to X-rays carried by said door, a fluorescent screen, means for supporting the screen outside of the door, and devices operated from behind the door for moving the screen vertically opposite said pane or from in front of said pane as desired.

6. In a device of the class described, the combination of a plurality of walls constituting a part of a cabinet for containing 85 electrical apparatus, and a door for closing the end of said cabinet, said door comprising in part a surface of material opaque to X-rays, a frame mounted upon the door and movable to a position extending above the 90 top of the door, and a pane of glass opaque to X-rays carried by said frame, said frame comprising in part a sheet of material opaque to X-rays, a fluorescent screen, means carried by said frame for supporting 95 the screen in front of the door, and devices operated from behind the door for moving said screen vertically as desired.

7. In a device of the class described, the combination of a plurality of walls constituting a part of a cabinet for containing electrical apparatus, a door for closing said cabinet, and an extension screen opaque to X-rays carried by said door and movable relatively thereto to project beyond the edge 105 of said door.

8. In a device of the class described, a cabinet having front, rear, side, top and bottom walls, a vertical partition between the front and rear walls dividing the cabinet into two compartments of unequal size, the larger of said compartments for containing apparatus for producing high tension current for X-ray work and the smaller of said compartments for containing switching and controlling mechanism for said apparatus, a vertical switchboard mounted in the smaller compartment on said partition, the side wall inclosing said smaller compartment consisting of a door hinged to the edge of said front wall, said door being opaque to X-rays, and a door in the rear wall of said larger compartment for affording access to the apparatus therein.

9. In a device of the class described, a cabinet having front, rear, side, top and bottom walls, a vertical partition between the front and rear walls dividing the cabinet into two compartments of unequal size,

- the larger of said compartments for containing apparatus for producing high tension current for X-ray work and the smaller of said compartments for containing switching and controlling mechanism for said apparatus, a vertical switchboard mounted in the smaller compartment on said partition, the side wall inclosing said smaller compartment consisting of a door 5 hinged to the edge of said front wall, said door being opaque to X-rays, a door in the rear wall of said larger compartment for affording access to the apparatus therein, and a screen opaque to X-rays and transparent to light rays carried by the door of the smaller compartment and movable relatively thereto.
10. In a device of the class described, a cabinet having front, rear, side, top and bottom walls, a vertical partition between the front and rear walls dividing the cabinets into two compartments of unequal size, the larger of said compartments for containing apparatus for producing high tension current for X-ray work and the smaller of said compartments for containing switching and controlling mechanism for said apparatus, a vertical switchboard
- 15 mounted in the smaller compartment on said partition, the side wall inclosing said smaller compartment consisting of a door hinged to the edge of said front wall, said door being opaque to X-rays, a door in the rear wall of said larger compartment for affording access to the apparatus therein, 30 and a movable fluorescent screen carried by the door of the smaller compartment.
- 20 11. In a device of the class described, the combination of a plurality of walls constituting a part of a cabinet for containing electrical apparatus, a door for closing said cabinet, an extension screen opaque to X-rays carried by said door and movable relatively thereto to project beyond the edge of said door, said extension screen being transparent to light rays, and a fluorescent screen carried by said extension screen and movable relatively thereto.
- 25 In witness whereof, we hereunto subscribe our names this 11th day of April, A. 40 50 D. 1914.

GEORGE R. HOGAN.
HECTOR P. MacLAGAN.
